UNITED STATES PATENT OFFICE.

HARVEY J. DIVEKEY, OF AURORA, ILLINOIS.

SANITARY PUMP BASE AND BRACKET FOR SINKS.

1,304,949.

Specification of Letters Patent. Patented May 27, 1919.

Application filed June 9, 1917. Serial No. 173,769.

To all whom it may concern:

Be it known that I, HARVEY J. DIVEKEY, a citizen of the United States, and a resident of the city of Aurora, county of Kane, and 5 State of Illinois, have invented certain new and useful Improvements in Sanitary Pump Bases and Brackets for Sinks, of which the following is a specification.

My present invention consists of a sink 10 provided with a base, which constitutes a part of and also supplies facilities for supporting small hand pumps in convenient relation to the sink.

The principal object of my invention is 15 the provision of a sink having a supporting base or bracket made integral therewith, whereby the pump standard may be conveniently and rigidly mounted upon the edge of said sink, or upon a stationary laundry- 20 tub, basin, or the like, and thus avoid the unsanitary conditions that arise when the pump base is a separate element and clamped upon the sink and avoid accumulations of dirt and other matter settling around the 25 joints. Another object of my invention consists in the novel construction of this base or bracket whereby the lower valve of the pump may be made readily accessible in order to eliminate a considerable portion of 30 the labor ordinarily necessary to knock down or disassemble the pump with respect to the sink. Another object of my invention is to provide a sink with an integral bracket or shelf which constitutes the base 35 proper of the pump and upon which the other elements of the pump are adapted to be mounted, said shelf also providing a drip apron for the pump.

Other advantages will be obvious after 40 an understanding of my invention is had, among which are economy of construction, dependability of operation and simplicity as regards the number of parts employed.

I prefer to accomplish the divers objects 45 of my invention in substantially the manner hereinafter set forth, reference being made to the accompanying drawings forming a part of this specification, in which,—

Figure 1 is a longitudinal front elevation 50 of a kitchen sink, showing my improvements applied thereto.

Fig. 2 is a fragmental longitudinal vertical section of the pump base drawn to an enlarged scale.

Fig. 3 is a top plan thereof, the pump 55 barrel being shown in section.

Fig. 4 is a fragmental end elevation of the pump base.

In the drawings I have illustrated a sink 5 of the ordinary type for domestic uses, 60 the upper edges whereof are provided with rolled-over flanges 6 that extend around the same and the rear portion whereof merges into an upright splashboard adapted to protect the wall. At one end of the sink this 65 rolled edge 6 merges into an integral bracket 7 that extends laterally outwardly therefrom in a horizontal plane slightly above the upper edge of the sink, said bracket having 70 its outer edge rolled over or turned down 75 as shown at 8 in Fig. 2 of the drawings, and the upper portion of the same adjacent the edge of the sink slopes downwardly to form a drip apron 9 over the rolled edge 6. The outer end portion of the bracket is semi-circular or curved, as shown in Fig. 3, and suitable side flanges, 10—10, are provided along the edges of the drip apron, which drip apron 9 extends from the central portion of the bracket downwardly to its junction with the sink so as to secure drainage 80 into the latter. The central portion of the bracket is provided with an opening 11, the upper edge whereof is rabbeted to provide 85 an annular shoulder 12. Suitable apertured embossments 13 are made upon the opposite sides of the opening 11 to receive clamping bolts, as will hereinafter more fully appear.

A collar 14, into which the well pipe 15 is secured, is provided with a valve seat 16 90 adjacent its upper end, that is of a diameter sufficient to permit it to rest upon the shoulder 12 heretofore mentioned and to lie flush with the upper surface of the integral bracket 7. A suitable flapper-valve is preferably placed upon this seat 16 of the collar 14, and comprises a disk 17 of leather or other suitable flexible material, that is provided with a concentric-recess 18 adjacent the edge, which extends sufficiently to provide the semi-detached central portion or lobe 19 to rest upon and cover the opening in the upper end of the collar 14. A weight 20 is secured by a screw or in any other suitable manner, upon the central lobe 19, 100 so as to assist in keeping the latter normally in contact with the valve seat on the collar and thereby close the opening.

Superimposed upon the outer edge of the washer or disk 17, is the annular collar 21, preferably of circular outline and provided with a downwardly projecting bead 22, 5 that is adapted to press against the outer portion of the disk 17. This annular collar 21 is provided with oppositely disposed bolt lugs 23, through which suitable bolts 24 are passed, and shanks of said bolts also extend 10 through openings provided in the bosses 13 heretofore alluded to, so that when the nuts are turned down tightly upon the screw-threaded ends of the bolts, the collar 21 will be pressed tightly against the disk 17 and 15 thereby lock the parts together upon the bracket or base 7, in a rigid and neat manner.

The usual pump cylinder 25 is secured by threading, swaging, sweating or otherwise, 20 in the annular collar or ring 21 and the pump is thus mounted complete upon the bracket in a manner so that it may be readily taken down for repair or replacement of any of the operating parts.

25 I do not desire to be limited to the precise construction of my device as shown in the drawings; which are merely diagrammatic for the reason that it is obvious many slight modifications of the structure therein may 30 be made. I therefore desire it understood that any such modifications are contem-

plated as being included within the scope of my invention as expressed in the appended claim.

What I claim as new is:—

35 Pump mounting means comprising a sink, an integral lateral extension projecting horizontally from the upper edge of one the sides of said sink, said extension being shaped to provide a drip into the sink and 40 having a central opening, a well pipe terminating adjacent said opening, a sleeve threaded on said pipe and having a disk-like flange at its upper end that rests on a shoulder formed in said opening whereby 45 said pipe is supported, a pump standard the lower end whereof is provided with a collar having lateral lugs and coacting with said flange, a gasket and flapper-valve interposed between said flange and the pump 50 members above the same; and clamping bolts passed through said lugs and said sink extension whereby a water-tight connection is made between said standard and the sink extension and said pump is supported solely 55 by the latter.

Signed at Aurora, county of Kane and State of Illinois, this 23 day of May, 1917.

HARVEY J. DIVEKEY.
